3 Claims. (Cl. 98—13)

1 The present invention relates generally to ventilating apparatus and more particularly to a modular structure comprising a plurality of polymorphic elements which may be readily and conveniently assembled to form a panel unit for a ventilating apparatus operable on the so-called pressure-displacement principle.

Ventilating apparatus operable on the pressure-displacement principle has received wide acclaim in recent years in many residential, commercial, and industrial air conditioning applications because such an apparatus is capable of delivering air at low velocity with wide-spread diffusion, uniform temperatures and without detectable draft.

Briefly, a pressure-displacement type ventilating apparatus, as such terminology is to be understood in connection with the present disclosure, includes a building structure, for example, an architectural structure or a railway car structure, which defines a primary plenum chamber to carry pressurized air and a space to be ventilated by such air and a panel unit defining a secondary plenum chamber is interposed therebetween. The wall between the secondary plenum chamber and the space to be ventilated preferably comprises a foraminous surface having a predetermined open area and the wall between the secondary plenum chamber and the primary plenum chamber preferably includes a valve controlled aperture through which controlled quantities of reduced pressure, low velocity air may be admitted into the secondary plenum chamber for diffused displacement outwardly through the foraminous wall into the space to be ventilated.

According to the general features of the present invention, the structural elements defining the secondary plenum chamber are modular in nature. A plurality of pan-like prototypes are provided, one species of which has a continuous surface, a second species of which has a surface with a valve opening therein and a third species of which has a foraminous surface. Each of the pan-like prototypes is provided with flanged beaded side wall portions which completely surround the surface portions and which may be coupled in quick-connect assembly with frame runners having coupling elements for receiving the pan-like prototypes in selectively assembled predetermined array.

In addition to the polymorphic nature of the pan-like prototypes, the frame elements are also standardized; corner brackets and splice plates being employed which are constructed in accordance with an identical basic pattern.

2 The use of a modular apparatus affords numerous advantages. The prototypal elements may be formed by the same dies and only additional form operations need be employed to convert the basic prototype into a distinct species. Thus, the elements of the modular structure may be stockpiled since any installation which prior to this invention would require custom building can easily be accommodated by ready combination of the polymorphic prototypes.

Moreover, the modular structure substantially eliminates all necessity for the employment of separate fastener means, thereby simplifying installation and permitting the use of elements which are greatly reduced in overall weight and which may be conveniently handled.

An important advantage resulting from the provision of a modular apparatus lies in the fact that not only is the material cost of the ventilation panel unit greatly reduced but manufacturing overhead is also cut down since location assembly of the polymorphic elements substantially reduces the shipping and fabrication space requirements ordinarily utilized in the place of manufacture.

It is, therefore, an object of the present invention to provide a modular pressure-displacement type ventilating apparatus.

A further object of the present invention is to provide a pressure-displacement type ventilating apparatus which may be economically produced from a reduced number of simplified elements and which may be readily installed on location by relatively unskilled personnel.

Another object of the present invention is to provide a plurality of prototypes for a modular ventilating apparatus which may be selectively assembled in any predetermined array to accommodate a wide variety of installation requirements.

Yet another object of the present invention is to provide pressure-displacement type ventilating apparatus comprised of standardized parts which may be manufactured at reduced cost with mass production methods and which may be subsequently stock-piled against future needs.

Many other features, advantages and additional objects of the present invention will become manifest to those versed in the art upon making reference to the detailed description which follows and the accompanying sheets of drawings, in which:

Figure 1 is a fragmentary cross-sectional view with parts in elevation and somewhat diagrammatic in character showing a ceiling structure

arrangement in a railway car employing a modular pressure-displacement type ventilating apparatus according to the present invention;

Figure 1A is a fragmentary cross-sectional view taken substantially on line A—A of Figure 1;

Figure 2 is a schematic and diagrammatic exploded view illustrating the principles of assembly incorporated in the provision of a modular pressure-displacement type ventilating apparatus according to the present invention;

Figures 3A, 3B and 3C are top plan views illustrating the structural features of three separate species of a pan-like prototype employed in a modular apparatus of the present invention.

Figures 4A, 4B and 4C are side views of the corresponding structures shown in Figures 3A, 3B and 3C.

Figure 5 is a greatly enlarged fragmentary cross-sectional view with parts shown in elevation showing a frame runner and coupling connection of the present invention;

Figure 6 is a view similar to that shown in Figure 5 but showing an alternative coupling connection;

Figure 7 is a fragmentary view with parts broken away showing the cooperative relationship between a corner bracket and frame runners of the present invention;

Figure 8 is a top plan view of a corner coupling junction as employed in the modular apparatus of the present invention;

Figure 9 is a perspective view of a splice plate according to the present invention; and

Figure 10 is a top plan view of the splice plate shown in Figure 8 but notched for converting the splice plate into a corner bracket as shown in dotted outline.

As shown on the drawings:

Referring first to Figure 1, a building structure indicated generally by the reference numeral 10 is shown which defines a primary plenum chamber 11 to carry pressurized and conditioned ventilating air and an enclosed space 12 which is to be ventilated. A panel-type unit is indicated generally by the reference numeral 13 and may be marketed separately as a product of manufacture.

The panel unit 13 has many applications in residential, commercial and industrial temperature conditioning installations and in such environments may be simply related to a duct 14 which defines the primary plenum chamber 11 for the ventilating system, however, the specific embodiment chosen for purposes of illustrating the principles of the present invention and depicted in somewhat diagrammatic form in Figures 1 and 1A relates to a ventilating apparatus as applied to railway vehicle equipment.

Thus, the building structure 10 may be considered to comprise the shell of a railway vehicle and the duct 14 suitably encased by insulation 16 may extend lengthwise of the vehicle as a part of the ceiling structure. It will be understood that the usual pressurizing and conditioning means may be situated in another portion of the vehicle in communication with the primary plenum chamber 11 to provide a supply of pressurized conditioned ventilating air thereto.

A sub-ceiling is provided in the vehicle and may be conveniently formed by the provision of a plurality of so-called acoustical pans 17 which are assembled in side by side relationship along the length of the car to enhance the decorative appearance of the car interior as well as to im-

prove the acoustic characteristics of the enclosed space 12.

The primary objective of a pressure-displacement ventilating apparatus is to effect uniform, draft-free, low-velocity air delivery throughout an entire occupied space, for example, throughout the railway vehicle herein illustrated. In order to selectively control the flow of air from the primary plenum chamber 11 into the space 12, a plurality of panel units 13 are spaced along the length of the duct 14 to provide a plurality of secondary plenum chambers 18 in interposed relationship between the primary plenum chamber 11 and the space 12 and in flow communication with both. In such manner, a stream of ventilating air from the primary plenum chamber may be introduced into the secondary plenum chamber at reduced pressure and low velocity whereupon the ventilating air may be further diffused as it is displaced outwardly from the secondary plenum chamber and into the space to be ventilated.

It will be readily apparent that many variations occur in building designs as well as in car building designs especially with respect to ventilation requisites. Hence, car builders and architects have heretofore prescribed separate specifications for each ventilation installation, thereby requiring custom built ventilating apparatus.

Although perfectly satisfactory from a performance standpoint, custom built ventilating apparatus, of necessity, is inherently quite expensive and involves the manufacture and sale of equipment under increased overhead costs.

According to the present invention, a modular panel unit is provided which includes certain polymorphic prototypes as basic units of construction, thereby making possible the provision of standardized panel unit runs which may be of any length desired to fulfill the peculiar requirements of any ventilating system installation.

As is shown schematically in Figure 2, a modular panel unit 13 utilizes a standardized sheet metal pan as a basic unit of construction. The basic unit is polymorphic, that is to say, it occurs in several distinct forms. Hence, the basic unit of construction may be defined as a pan-like prototype, in other words, a primary form is provided which occurs in the form of several distinct species.

Referring more particularly to Figures 3 and 4 and in further reference to the schematic illustration of Figure 2, a plurality of pan-like prototypes are shown including a first species 20 which may also be referred to hereinafter as a standard pan, a second species 21, which may also be referred to as a valve pan, and a third species 22 which may also be referred to as a distribution pan.

As will be evident upon making reference to Figures 3A, 3B, 3C, 4A, 4B and 4C, the basic pattern of construction of each of the prototypes is identical. The first species 20 or standard pan is provided with a continuous unbroken surface 20a. As shown in Figures 3A and 4A, a handle 23 may be appended to a selected number of the standard pans 20 if desired to facilitate installation of the last pan in a panel unit.

The second species 21, or valve pan, may be subjected to an additional blanking or forming operation so as to define a pair of valve apertures 21a, 21a in spaced aligned relationship relative to the surface of the pan with a spindle aperture 21b lying therebetween. In order to

add strength to the surface of the valve pan 21, a flanged rib 21c may be formed around the peripheral portions of each of the valve apertures 21a, 21a. It will be appreciated that the broken view of the valve pan 21 shown in Figures 3B and 4B includes approximately one-half of the actual area defined by each of the valve apertures 21a, 21a, however, further detailing is believed to be unnecessary to the understanding of the principles of the present invention.

The third species 22 or distribution pan is subjected to an additional blanking operation to provide a foraminous surface 22a defining an open area bearing a predetermined percentage ratio to the closed surface area, the open area being defined by a plurality of perforations 22b.

In each instance, the various species 20, 21, 22 of the pan-like prototype are provided with surrounding side walls 24 which are flanged upwardly and provided with an inwardly extending peripheral bead 26, the opposite side of which forms a groove 27. Each of the side walls 24 may be provided with a cut-out corner portion 24a to facilitate forming operations and to make subsequent assembly of the modular apparatus more convenient.

Referring again to Figures 1 and 2, the utility of the second species valve pan 21 may be enhanced by integrating therewith one or more perforated trough-shaped diffusers 28, one of which being firmly assembled to the surface of the valve pan 21 and lying in registry with each of the valve apertures 21a.

A bushing, the details of which are not shown, is also assembled on the valve pan 21 in registry with the spindle aperture 21b and threadedly carries a movable adjusting bolt 29 which mounts a valve plate 30 thereon for selectively adjustable reciprocable movement relative to the valve apertures 21a. By adjusting the plate 30 towards and away from the valve pan 21, the apertures 21a will be variable throttled, thereby controlling the flow of air from the primary plenum chamber into the secondary plenum chamber. A plurality of resilient elements 31 may be interposed between the valve pan 21 and the valve plate 30 to normally bias the valve plate upwardly, thereby precluding the occurrence of rattling noises and serving to guide the valve plate 30 in its reciprocatory path.

Referring now more specifically to Figures 5 and 6 in connection with Figures 1 and 2, the modular panel unit 13 is shown as including a frame having side members 32 and end members 33 defined by a standardized frame runner 34. Each of the frame runners includes a snap retainer 36 which is more or less W shape and which is formed along each of its marginal edge portions into the shape of a bead and groove as at 36a and 36b to receive correspondingly beaded and grooved elements in mating relationship therewith.

The retainer 36 may be firmly affixed to the side walls of a duct structure as, for example, the duct 14 by means of a plurality of fasteners 37. In this particular embodiment, an additional element for the frame runner is employed which may be termed a backing plate 38.

The backing plate 38 is formed along one marginal edge thereof to define a bead and groove portion 38a and has a turned over marginal portion on the other edge thereof as at 38b. The backing plate 38 and the retainer 36 may be integrated by spot welding as at 48.

In attaching the frame runners 34 to the side

walls of a duct 14 in a railway vehicle, a felt striping 39 may be interposed between the duct walls and the backing plate 38 and the fasteners 37 will extend through the retainer 36, the backing plate 38, the felt striping 39 and the side walls of the duct 14.

Any desired length of end members 33 and side members 32 may be easily accommodated merely by providing a frame runner of appropriate dimension. Should the length required exceed the usual dimension of a conventional frame runner held in stock, a splice plate 41 may be provided as is shown in Figure 9 to join several frame runners in end to end assembly. An assembly of end members 33 and side members 32 may also be joined by a coupling connection afforded by a corner bracket 41' as is shown in Figures 7 and 8.

The corner bracket 41' and the splice plate 41 are of identical construction except that the corner bracket 41' is bent 90°. In each instance, an originally flat piece of metal is appropriately sheared to permit formation of two pair of legs, the legs being indicated by the reference numerals 42a and 42b. Each of the legs 42a and 42b includes a back 42c turned up from the center portions of the flat metal with a leg 42d bent at right angles thereto and an arm 42e which is bent back upon the leg 42d at an acute angle relative thereto. The angle between the arm 42e and leg 42d is preferably the same as the angle included between the V-shaped components of the W-shaped retainer 36.

The legs 42a and 42b are joined by a centrally disposed body portion 42f. The leg portions 42d of the legs 42a and 42b extend the entire length of the splice plate 41 and thereby define strengthening flange portions for the body 42f.

If the splice plate 41 is to be converted into a corner bracket 41', a V-shaped notch shown on Figure 10 and indicated by the reference numeral 43 may be cut out of each of the flanged portions opposite the body 42f in the leg portions 42d whereupon the splice plate 41 may be bent into right angular form to form a corner bracket 41' as shown by the dotted lines.

In coupling a pair of frame runners in end-to-end relationship, the legs 42a of a splice plate 41 are inserted into the V-shaped components of the W-shaped retainer 36 on one frame runner 34 and the legs 42d of the splice plate 41 are inserted into the retainer 36 of a second frame runner 34.

As is indicated in Figures 7 and 8, the backing plate 38 preferably extends beyond the ends of the retainer 36. When a pair of frame runners 34 are in assembled relationship, the ends of the retainers will be spaced apart by the width of the body 42f and the backing plates 38 will engagingly abut one another.

If an end member 33 and a side member 32 are to be coupled via a corner connection, the same coupling procedure is followed.

Referring further to Figures 5 and 6 in connection with Figures 1 and 2, several installation applications are shown.

In Figure 5, an acoustic pan 17' is shown which is patterned after the distribution pan species of prototype, however, a layer of acoustical material 46 is inserted within the pan to enhance the sound absorbing characteristics thereof. The acoustic pan 17' is provided with upstanding flanged and beaded peripheral walls to be received in coupled relationship by the beaded portion 38a of the backing plate 38 and the beaded portion 36b of the retainer 36.

7 It will be noted that the distribution pan 22 is mounted to lie flush with the acoustic pan 17. Thus, an unbroken sub-ceiling may be defined by the acoustic pan 17 and the distribution pan 22 to improve the overall decorative effect achieved within the space 12.

In Figure 6, an architectural installation is depicted showing a ceiling 47 suitably defined by an appropriate building material such as plaster or the like in which a plaster ground or clip 43 is embedded. The clip 43 is provided with a beaded coupling portion 48a to be received by a frame runner 34.

It will be understood that a clip similar to the clip 43 and indicated by the reference numeral 48' (Figure 1) may also be secured by fastener 49 to a wall surface for connecting acoustic pans 17 or the like in abutting engagement with the surface.

In practice, the specifications of any particular 20 ventilating system installation may be easily met by cutting suitable lengths of frame runners 34 to appropriate length and providing the required number of prototypes in the forms of standard pans 20, valve pans 21 and distribution pans 22. It will be apparent that each of the species of 25 the prototypal pans may be stock-piled as may be the frame runners.

If desired, all of the components may be 30 shipped to job location in disassembled form whereupon the frame runners 34 may be readily connected to the side walls of a duct 14 or to an appropriate building structure.

A selected number of first species standard 35 pans 20 and second species valve pans 21 are positioned in predetermined array on one side of the frame runners 34 and the beaded flanged peripheral side walls thereof are mated with the coupling elements of the frame runners 34. In this manner, the open side of the duct 14 is closed, or in other words, a wall is provided for the primary plenum chamber 11. It may also be noted that the last standard pan 20 to be inserted may be equipped with the handles 23 as previously explained so that the pan may be positioned above the frame runners and pulled down into assembled relationship therewith to complete the closure of the duct.

The third species distribution pans 22 are positioned on the other side of the frame runners 34 and, hence, lie in spaced relationship to the closed wall of the duct 14. It will be understood, that if necessary, a number of the standard pans 20 may also be situated on the frame runners 34 adjacent the third species distribution pans 22 if the prototypes are employed along the entire length of a run.

In this manner, the distribution pans 20 form a portion of one wall of the space 12 and all of the prototypes including the standard pans 20, the valve pans 21, the distribution pans 22 and the frame runners 34 together define a secondary plenum chamber 18 which is interposed between the primary plenum chamber 11 and the space 12.

Thus, pressurized, conditioned ventilating air carried in the primary plenum chamber 11 may be introduced into the secondary plenum chamber 18 as regulated by the valve plate 36 which is in control of the flow of air through the apertures 21a and such air will be diffused by the diffusers 28 as it enters the secondary plenum chamber 18.

Air in the secondary plenum chamber 18 will be displaced outwardly and further diffused through the open area defined by the perforations 75

22b in the foraminated surface 22a of the third species distribution pans 22.

Although the preferred embodiment herein described in considerable detail for purposes of illustration could conceivably be modified as to various details of construction by a person skilled in the art, it should be understood that I propose to embody within the scope of this patent all such modifications as reasonably and properly come within the scope of my contribution to the art.

I claim as my invention:

1. In a modular pressure-displacement type ventilating apparatus, a plurality of pan-like prototypes, one species comprising a standard pan, a second species comprising a valve pan dimensionally similar to said standard pan with a valve opening therein, and a third species comprising a distribution pan dimensionally similar to said standard pan and having a foraminated surface, each of said pan-like prototypes having flanged wall portions bent away from and surrounding each of said surfaces, frame runners having coupling elements on opposite sides thereof engagingly receiving the flanged wall portions of the prototypes in coupling relationship, a number of said first species and at least one of said second species of said prototypes being assembled on one side of said frame runners, and at least one of the third species assembled on the other side of the frame runners, all of said prototypes together with the frame runners forming an enclosed air chamber, duct means connected to said second species and flowing air into said chamber through said valve opening, valve means carried by said second species of said prototypes in control of said valve opening therethrough to regulate the flow of air into said air chamber, whereby a restricted flow of air introduced into said air chamber is diffused outwardly through the foraminous surface defined by said third species of said prototypes.

2. In a railway car, means providing an open sided duct in the ceiling structure of the car, a plurality of pan-shaped acoustic ceiling elements forming a sub-ceiling in the car extending inwardly and terminating short of the duct, a plurality of frame runners connected to the inner side walls of the duct, coupling elements carried by the frame runners on opposite sides thereof, and a plurality of pan-like prototypes, one species comprising a standard pan, a second species comprising a valve pan dimensionally similar to said standard pan with a valve opening formed therein, and a third species comprising a distribution pan dimensionally similar to said standard pan and having a foraminated surface, each of said pan-like prototypes having flanged wall portions bent away from and surrounding each of said surfaces, said coupling elements of said frame runners engagingly receiving the flanged wall portions of the prototypes in coupling relationship, a number of said first species and at least one of said second species of said prototypes being assembled on one side of said frame runners, and a number of said first species and at least one of said third species of said prototypes being assembled on the other side of said frame runners in flush relationship with said sub-ceiling to close the open side of the duct, all of said prototypes together with the frame runners forming an enclosed air chamber independent of said duct, valve means carried by said second species of said prototypes in control of the valve opening therethrough and regulating the flow of air from said duct means into said enclosed air chamber,

whereby a restricted flow of air introduced into said air chamber is diffused outwardly through the foraminous surface defined by said third species of said prototypes into the interior of the railway car.

3. In a ventilating apparatus as defined in claim 1, said coupling elements of said frame runners comprising oppositely extending spring fingers and said flanged wall portions of said prototypes having beads formed thereon coacting with said spring fingers to effect a snap-in coupling assembly of said prototypes with said frame runners.

EDWIN J. KUREK.
